COLLAPSIBLE CONTAINER

Clarence W. Vogt, New York, N. Y., assignor, by
mesne assignments, to Owens-Illinois Glass
Company, Toledo, Ohio, a corporation of Ohio

Application December 17, 1935, Serial No. 54,794

5 Claims. (Cl. 229—53)

This invention relates to collapsible containers which may be shipped or stored in an empty or flat condition and opened up to the desired size and form for filling. The invention relates more particularly to the type commonly known as bags in which all or substantially all of the walls are of flexible material and in which the sections are folded inwardly as pleats in collapsing the bag.

10 The main object of my invention is to provide a bag made of inexpensive material and which is substantially sealed in an inexpensive manner when in collapsed condition so as to prevent the entry of foreign matter and prevent contamination of the inner surfaces of the walls.

15 A further object is to provide a bag having a pleat or fold in one wall so constructed and so arranged that it may be provided with a filling or emptying opening intermediate of the ends of the pleat and which may be opened by the spacing of the opposite walls of the pleat or fold.

20 As one important feature of my invention the bag is formed of a tube of sheet material folded longitudinally to form reentrant lateral folds connecting the front and rear walls of the tube, both ends of the tube being sealed by folding or by a separate sealing member prior to filling, and the filling and emptying being effected through a pleat adapted to be cut, unsealed or opened up to permit the passage of the material into or out of the tube.

25 By means of my invention the complete bag may be made and sealed at opposite ends at low cost, shipped or stored in this condition, readily opened and supported for filling, and readily opened for dispensing the contents in whole or in part.

30 The filling of the bag is effected through an opening in the pleat whereby the filling serves to distend the bag to its full capacity and without applying strain tending to separate the two side walls of the pleat and between which the filling material is introduced. The bag after being filled may be stored or shipped with or without being inserted or packed in outer containers or cases adapted for one or any desired number of such filled bags.

35 My improved bag may be made of any suitable flexible material. If the bag is to be used for dry powders it is not essential that the sheet material be impervious to liquids and for such purpose ordinary paper may be employed. If the bag is to be used for liquids the sheet material should be impermeable to liquids either by reason of the nature of the base material forming the

sheet or by reason of surface coatings or other treating compounds.

The ends of the bag may be sealed in various ways, but preferably by means of metal clips which may be applied before or after the superposed walls forming the tube at the end of the latter are bent back upon themselves to form a seam.

40 In the accompanying drawing I have illustrated certain embodiments of my invention and also illustrated the parts and steps which may be employed in making the bag.

In the drawing:

Fig. 1 is a perspective view of a sheet which may be employed for making three of the side walls of the bag,

Fig. 2 is a perspective view of a sheet which may be employed for making the other side wall and forming the pleat,

Fig. 3 is a perspective view of a tube section resulting from sealing the sheets together, but before closing the ends,

Fig. 4 is a perspective view of a closed and distended bag,

Fig. 5 is a perspective view illustrating the method which may be employed for filling the bag,

Fig. 6 is a similar view showing the filling opening sealed,

Fig. 7 is a transverse section on the line 7—7 of Fig. 5, the pleat being folded outwardly of the length of the bag,

Figs. 8 and 9 are sectional details showing the sealing of the ends of the bag,

Fig. 10 is a perspective view of a sealing device for the opening of the pleat,

Fig. 11 is a perspective view similar to Fig. 3, but showing a slight modification,

Fig. 12 is a view of the form shown in Fig. 11, but with the end of the bag sealed,

Fig. 13 is a perspective view of a sealing device which may be employed in place of that shown in Fig. 10, and

Fig. 14 is a section similar to Fig. 7, but showing an alternative construction.

45 In forming the bag there are employed two sheets 10 and 11 of thin flexible material and which may be of a thickness and strength depending upon the size of the bag to be formed, and of a character so far as permeability is concerned dependent upon the nature of the liquid or other material for which the bag is to be used.

50 The sheet 10 is rectangular and of a length substantially equal to the desired length of the bag when the latter is in collapsed condition.

55

It is of a width slightly greater than the width of three sides of the bag when the latter is in distended condition. This sheet includes a center panel 12 corresponding in width to what 5 may be considered the back of the bag, and two panels 13 each of a width substantially equal to the two side walls of the bag. The sheet may have fold lines indicated in dash lines between these separate panels, and the panels 13 may have fold lines midway between their opposite edges so as to facilitate the infolding of the side walls. At opposite edges of the sheet are narrow flaps or marginal portions 14 which may have adhesive applied thereto for the securing of the other sheet 11 in case there is no adhesive applied 10 to the parts of the sheet 11 with which the edge portions of the sheet 10 engage.

The sheet 11 is of a width substantially equal to the panel 12 of the sheet 10 and may serve as 20 a front wall of the bag. It has adhesive applied along the opposite edges of at least the part going to make up the pleat, and may have it along the entire length of said edge portions.

The sheet 11 is of a length somewhat greater 25 than that of the sheet 10 and has three fold lines extending transversely thereof adjacent to but spaced from one end to form two sections 15 which may be brought together to form the pleat hereinbefore referred to. The difference in 30 length of the sheets 10 and 11 is substantially equal to the combined widths of the two transverse sections 15.

In assembling the two sheets to form a tube the edge portions of the sheet 11 are adhesively 35 secured to the edge portions 14 of the sheet 10, and the panels 13 are bent at their edges and intermediate of their edges to form the infolds as shown in Fig. 3. The sheet 11 is folded on the three transverse fold lines so as to form the pleat 40 16 also shown in Fig. 3. It will be understood that the tube as shown in Fig. 3 may be made merely by the use of two rectangular sheets shown in Figs. 1 and 2 or that said rectangular sheets 10 and 11 may be merely successive sections 45 of the sheet material which are progressively folded, brought together and adhesively secured to form a long continuous tube which may be cut into successive sections of the type shown in Fig. 3 as rapidly as the long tube is 50 produced.

After making the tube as shown in Fig. 3 the superposed layers on each end are sealed together so as to close the bag at both ends. Adhesive 55 may be applied to the surfaces which come together at the end of the bag, or in some cases the adhesive may be omitted and some other sealing means employed.

In Fig. 8 there is shown a U-shaped metal clip 17 which may be pinched onto the end of the bag to effectively close it.

In Fig. 9 the end walls are shown as being slightly longer so as to provide sufficient material for folding over to make a seam 18, the superposed layers of which may be glued together, or these superposed layers may be pinched and held together by a U-shaped metal clip.

The distance between the transverse pleat 16 shown in Fig. 3 and the adjacent end of the tube is preferably somewhat greater than one-half 70 the width of a side wall 13 so that upon distending the bag as shown in Fig. 14 the pleat will come along the angle of intersection of the top and front wall of the bag, and the transverse seal or seam will extend transversely across the top.

In sealing the sheets 10 and 11 together the two

ends of the pleat have their superposed sections 15, 15 glued together, but the pleat will open inwardly at the inner side. As the pleat cannot open at its ends or at its outer edge, the bag when filled substantially to capacity will permit the side walls of the pleat to lie in closely juxtaposed positions.

For filling the bag an opening is provided in the outer or fold edge of the pleat. This opening may be produced in the sheet 11 at the proper point before the bag is made, or may be cut in the pleat after the bag has been completed.

As shown in Fig. 2 the sheet 11 is provided with an opening 19 so positioned that it forms a substantially semi-circular notch or recess in the outer edge of the pleat as shown in Figs. 3 and 4.

For filling the bag a filling tube, funnel or the like may be inserted through the opening as shown in Fig. 5 and as the material enters the 20 bag it will be distended from its original flat collapsed condition to its distended condition. The bag may be supported by a pair of clamps gripping the opposite end portions of the pleat, and as the two surfaces are here sealed together 25 it will do no harm if the clamps pierce the material or even enter previously formed perforations therein to prevent slipping of the pleat out of the clamps as the bag is distended by the entering material. For readily flowable materials the 30 bag will be distended by the material as it enters if the bag walls be thin or freely flexible or if the material be supplied under pressure or at high velocity. If the bag walls be comparatively stiff or if the filling material be light or not readily 35 flowable, the bag may be distended before filling. After the filling of the bag and the removal of the filling tube, funnel or the like, the side walls of the pleat will come substantially together and the pleat may be folded flat against the top wall 40 or downwardly against the front wall of the bag.

For some materials it may not be necessary to seal the opening 19, but for liquids it is preferable to seal the opening. For this purpose there may be employed a substantially U-shaped clip 21 45 shown in Fig. 10 of a size somewhat greater than that of the opening and adapted to be pinched or sealed onto the pleat 16 to completely cover the opening as shown in Fig. 6. This clip may be made of sheet metal and may be pinched in place 50 either by hand or by means of a suitable tool, or it may be made of paper or other more flexible sheet material and may be coated on its inner side with adhesive so that upon pinching it onto the pleat it will hermetically seal the opening.

In Fig. 13 I have shown a disc 22 having adhesive upon one surface thereof and which may be folded transversely and used as the seal. Upon applying the adhesive to the sheet 11 to provide for the sealing together of the ends of the pleat, an annular strip of adhesive may also be applied around the hole 19 as shown in Fig. 11 and in that case the disc or other piece of sheet material which is used as the closure need not have adhesive directly applied thereto.

As previously noted it is not essential that there be adhesive employed in sealing together the ends of the bag as this may be done by a metal clip with or without folding over the superposed layers. In some cases I may use adhesive exclusively at the ends and without the metal clip. As shown in Fig. 11 the ends of the sheets 10 and 11 may be provided with transverse strips of adhesive 23 which may be of a thermo-

plastic character so that upon pressing the walls together, as shown in Fig. 12, and by applying the required amount of heat, the end of the bag will be effectively and completely closed and sealed. For most purposes this is not as satisfactory as bending over the walls as shown in Fig. 9 and with a metal clip to hold them in the bent sealed condition.

I have previously referred to closing the filling opening by a closure member which merely covers the hole and the area around it. The sealing may be effected by bending the pleat intermediate of its edges and holding it in this sealed condition by a U-shaped metal clip, such as the clip 17 used for sealing the ends.

When it is desired to open the bag a corner of the pleat 16 may be cut off, or the sealing closure may be pulled off, or in some cases the pleat employed as a tab for tearing the bag open if the entire contents is to be dispensed at once.

If the bag is to be used for a liquid, and if the walls of the bag be formed of coated paper, it is possible that in some instances the liquid may seep into the opposite edges of the sealing flaps 14 and to such an extent as would cause slight leakage or discoloration. In order to prevent any cut edges or uncoated surfaces from contact with the material within the bag the sealing flaps 14 shown in Fig. 1 may be made of approximately double width and folded first inwardly and then outwardly as shown in Fig. 14. This might permit a slightly greater distention of the bag when filled, but this is immaterial if only a predetermined amount be put in the bag or if the bag walls be supported by an outer casing or carton.

In the forms illustrated the sheet 11 is of substantially the width of the panel 12. It will of course be obvious that the sheet 11 might be made very much narrower in width, and the sheet 10 be made wider, so that marginal portions of the sheet 10 would cooperate with the sheet 11 in forming the front wall of the bag. In that event the pleat 16 instead of extending the full width of the front wall would extend only a portion of such width as the length of the pleat will correspond directly with the width of the sheet 11. In some cases the sheet 11 may be made comparatively narrow and the opening 19 be merely a slit extending the full length or

substantially the full length of the fold, except for the marginal seals.

Having thus described my invention, what I claim as new and desire to secure by Letters Patent is:

1. A container comprising a tube of flexible sheet material, including two sections, one adapted to form three walls of the tube and the other adapted to form a fourth wall, said last-mentioned section having a transverse pleat intermediate of its ends, and separate sealing strips securing together the sheets at the end of the tube to close the seam. 5

2. A bag formed of a tube of flexible sheet material having infolded opposite sides, separate members connecting together opposite walls of the tube at opposite ends to close the tube at said ends, and a pleat extending transversely of one wall of the bag, said pleat being sealed at its ends and having its outer folded edge provided with a filling or dispensing opening. 10 15

3. A bag formed of a tube of flexible sheet material having infolded opposite sides, separate members connecting together opposite walls of the tube at opposite ends to close the tube at said ends, a pleat extending transversely of one wall of the bag, said pleat being sealed at its ends and having its outer folded edge provided with a filling or dispensing opening, and a closure for said opening. 20 25

4. A bag formed of a tube of flexible sheet material having infolded opposite sides, separate members connecting together opposite walls of the tube at opposite ends to close the tube at said ends, a pleat extending transversely of one wall of the bag, said pleat being sealed at its ends and having its outer folded edge provided with a filling or dispensing opening, and a U-shaped clip enclosing a portion of the folded edge of the pleat and constituting a closure for 30 35 40 said opening.

5. A container comprising a tube of flexible sheet material, said tube being normally in flat collapsed condition, one side of said tube having means intermediate of the ends thereof for forming an outlet opening and pouring spout, and the ends of said tube having sealing strips for holding the opposite sides of the tube together in closed position. 45
